UNITED STATES PATENT OFFICE

95,408

DESIGN FOR A COVER FOR CRANK OPEN- ING IN AN AUTOMOBILE RADIATOR

Harry Golden, New York, N. Y.

Application September 28, 1934, Serial No. 53,429

Term of patent 3½ years

To all whom it may concern:

Be it known that I, Harry Golden, a citizen of the United States, residing at New York, county of New York, State of New York, have invented a new, original, and ornamental Design for a Cover for Crank Opening in an Automobile Radiator, of which the following is a specification, reference being had to the accompanying

drawing, forming a part thereof, in which, Figure 1 is a face view showing my new design and, Figure 2 is a side elevational view thereof.

I claim:

The ornamental design for a cover for crank opening in an automobile radiator, as shown.

HARRY GOLDEN.
